KEY HOLDER

Leonidas J. Mitchell, Farmdale, Barboursville
District, W. Va.

Application November 7, 1940, Serial No. 364,684

5 Claims. (Cl. 70—456)

This invention relates to improvements in the class of key holders, and its objects, more specifically stated, are as follows:

First, to provide a key holder suitable for carrying in pockets of personal garments, in purses or elsewhere, which would occupy a minimum of space consistent with a high degree of utility and efficiency.

Second, to provide a key holder comprising a minimum number of parts consistent with attractive appearance and faultless utility.

Third, to provide a key holder that, owing to its general design and operating features, would appeal to the desires, tastes and habits of either men or women.

Other objects and advantages will appear in the following specifications, reference being made to the accompanying drawing, in which:

Figure 1 is a view in perspective of my key holder with the flexible casing partly broken away.

Figure 2 is a view in perspective of a single loop key ring mounted in a reinforcing plate.

Figure 3 is a view in perspective of a double loop key ring mounted in a modified form of reinforcing plate.

Figure 4 is a view in perspective of another modified form of reinforcing plate and ring.

Figure 5 is an end view in elevation of the reinforcing plate shown in Fig. 2 with the key ring removed.

Figure 6 is an end view in elevation of the key holder shown in Fig. 1 with the casing in closed position.

Figure 7 is a similar end view showing a modified form of the flexible cover or casing for the key holder.

Figure 8 is a longitudinal side view of the key holder shown in Fig. 3 with the casing partly in section.

Figure 9 is a front elevation of the overlapping ends of the key ring showing the tapered formation of said ends.

Figure 10 is a similar view showing the overlapping end portions as reduced along their longitudinal axis.

Figure 11 is a plan view of the overlapping ends of the ring shown in Fig. 10.

Referring more particularly to Figure 2, 12 and 12a designate a pair of parallel legs formed by bending a strand of resilient wire intermediate its ends to form a plurality of loops or U-shaped members 15, 16 and 26. The U-shaped member 26 is disposed at substantially a right angle to a plane passing through the legs 12 and 12a.

The U-shaped member 16 has the usual bight portion connected by a leg 39 to one end of the U-shaped member 26. A leg 31 of the U-shaped member 15 is connected to the other end of the U-shaped member 26.

A flat metal plate is bent U-shaped to conform to the shape of the U-shaped member 26 to form a saddle 14 to receive the free ends of the keys 21 when said keys have been placed in the holder.

10 This saddle has its free ends as shown at 32 bent inwardly upon itself and is provided with sockets 34 to receive the respective legs 12 and 39 and the legs 12a and 31.

15 Holes 13 are punched through the inturned portions 32 and the arms of the saddle 14, as shown, to receive rivets, staples or cleats 20.

The free ends of the legs 12 and 12a are bent inwardly at right angles to each other and are placed in overlapped relation as shown at 11, particularly in Figs. 9, 10 and 11. In Fig. 9 the free ends are sheared off at an angle so that when the ends overlap the cross sectional area of the overlapped portion will be substantially the same as the cross sectional areas of the legs 12 and 12a.

20 In Figs. 10 and 11 is shown a modified form of the overlapped ends in which a semi-circular portion of each free end is cut away. The free ends are overlapped so that the overlapped ends 25 will again have substantially the same cross sectional area as the legs 12 and 12a. Other forms of overlapped ends may be employed for the purpose.

25 Referring more particularly to Fig. 3 it will be seen that a pair of key rings are employed and these rings extend in opposite directions from each other and are supported by the saddle 14a which is a slight modification of the saddle shown in Fig. 2, although substantially the same

30 elements are employed in the key rings such as the pair of legs 12 and 12a, the U-shaped members 15 and 16 and the U-shaped member 26. However, the free ends of the arms of the

35 U-shaped saddle 14a are provided with a pair of inturned portions 35 and 36 spaced from each other with sockets 37 and 38 to receive the legs 12 and 39, and 12a and 31. It will be noted that the bight portions of the U-shaped members 16

40 are in abutting relation as are the bight portions of the U-shaped members 15.

45 The saddle 14a is curved to conform to the curvature of the U-shaped member 26. The inturned portions 35 and 36 of the arms of the saddle are provided with passages 13 to receive rivets 20 for the purpose of securing the

U-shaped members 15 and 16 against displacement and for a purpose which will be presently explained.

Referring more particularly to Fig. 4 it will be seen that a piece of resilient wire is bent to form a pair of parallel legs 40 and 41 which have their free ends in overlapped relation as shown at 11a. These legs are connected by a U-shaped member generally designated by the numeral 26a which extends below a plane passing through the legs 40 and 41 and at an obtuse angle to said plane.

A saddle 19 is formed of sheet metal and is provided with a pair of inturned portions 42 at the free ends of the arms of said saddle to receive the legs 40 and 41. One side edge of the saddle is also provided with inturned portions 43 to form sockets to receive the legs of the U-shaped member 26a which is curved to conform to the curvature of the saddle 19.

As shown more particularly in Figs. 1, 6, 7 and 8 a cover or casing 23 houses the key ring and the saddle and is secured at its side edges to the arms of the saddle by means of rivets 20. These rivets perform the double function of securing the side edges of the cover or casing to the saddle, and of securing the inturned portions at the free ends of the arms of the saddle.

In Fig. 6 is shown a separable fastener designated by the numerals 45 and 46 usually in the form of a socket and a pin. In this instance the side walls of the casing are brought into registration and into flat contact above the ends of the keys 21 and the separable fastener is then pressed together.

In Fig. 7 the ends of the casing 23 are laid in over-lapped relation above the keys and in a substantially horizontal position after which the elements of the separable fastener 47 are forced together.

In this type of construction the handles 48 of the keys are located outwardly so that the usual openings in the handles will be received by the overlapped portions 11 of the ring while the free ends of the keys, as shown in Fig. 8, will rest and be supported by the saddle 14 or 14a. The legs 12 and 12a or the similarly positioned legs 40 and 41 of the key ring will act as side rails for aiding in maintaining the keys in position. The keys are inserted by prying open the overlapped ends 11 of the ring so that the opening in the handle of the key may be received by one of the ends and the key is then moved to a position where it will be free of the other end of the overlapped portion so that the overlapped portion will be permitted to spring back into place due to the tension exerted by the resiliency of the wire.

While only one rivet is employed for securing the casing or cover 23 to the saddle 19 in Fig. 4, nevertheless, the length of the saddle is such as to prevent movement of the casing when riveted to the saddle.

The casing or cover may be formed of leather or any suitable composition material suitable for the purpose and due to the flexibility of these materials they may be easily bent along the free edges to the position shown in Figs. 6 and 7.

The saddles 14, 14a or 19 not only perform the function of supporting the free ends of the keys but they also provide means for rigidly holding the legs of the key ring in parallel relation.

Figures 2 and 4 show single key rings, while Figure 3 discloses a double key ring in which the overlapped ends 11 of the legs 12 and 12a operate as a holder for the keys when the keys are disposed in parallel position with the inner free ends of the keys resting on the saddle 14a.

I claim:

1. A key holder comprising a piece of resilient wire bent intermediate the ends thereof into a plurality of U-shaped members, and a strip of flat metal curved to form a U-shaped saddle to support the free ends of keys, the ends of the arms of the saddle being bent upon said arms to engage around the legs of a pair of the first-mentioned U-shaped members, the free ends of the wire being located in overlapping relation and adapted to be separated to receive keys.

2. A key holder comprising a piece of resilient wire bent intermediate the ends thereof into a plurality of U-shaped members and a strip of flat metal curved to form a U-shaped saddle to support the free ends of keys, a pair of the first-mentioned U-shaped members being disposed in parallel relation, the ends of the arms of the saddle being bent upon said arms and provided with spaced sockets to receive the legs of the pair of U-shaped members, the free ends of the wire being located in overlapping relation and adapted to be separated to receive keys.

3. A key holder comprising a piece of resilient wire bent intermediate the ends thereof into a plurality of U-shaped members and a strip of flat metal curved to form a U-shaped saddle to support the free ends of keys, a pair of the first-mentioned U-shaped members being disposed in parallel relation, the ends of the arms of the saddle being bent upon said arms and provided with spaced sockets to receive the legs of the pair of U-shaped members, the free ends of the wire being located in overlapping relation and adapted to be separated to receive keys, the other U-shaped member being aligned with the curved edge of the saddle.

4. A key holder comprising a strand of resilient wire bent intermediate the ends thereof to form a U-shaped member and a pair of parallel legs, the free ends of the legs being bent inwardly towards each other in overlapping relation, said U-shaped member being located at an angle to a plane passing through the parallel legs, and a saddle formed of a strip of flat metal bent into U-shaped formation, the free ends of the U-shaped saddle being bent around the legs, the first-mentioned U-shaped member being disposed in alignment with an edge of the saddle.

5. A key holder comprising a piece of resilient wire bent intermediate the ends thereof into a plurality of U-shaped members and a strip of flat metal curved to form a U-shaped saddle to support the free ends of keys, a pair of the first-mentioned U-shaped members being disposed in parallel relation, the ends of the arms of the saddle being bent upon said arms and provided with spaced sockets to receive the legs of the pair of U-shaped members, the free ends of the wire being located in overlapping relation and adapted to be separated to receive keys, means connecting the in-bent portions of the arms of the saddle to said arms.
